APPARATUS FOR CLEANING FABRICS

Russell A. Hetzer, Cincinnati, Ohio, assignor to
 The American Laundry Machinery Company,
 Cincinnati, Ohio, a corporation of Ohio

Application June 18, 1930, Serial No. 462,061
 In Great Britain May 29, 1930

17 Claims. (Cl. 68—38)

5 My invention relates to apparatus for treating fabrics and, particularly, to a method of treating fabrics with a volatile detergent having a low boiling point and to apparatus for removing the foreign matter from the detergent after the treating operation whereby the same detergent may be used in subsequent operations with but little loss in the volume thereof.

In fabric treating machines, it is desirable to 10 be able to repeatedly use the same detergent and to have the detergent equally effective in each operation or to use the same supply of detergent over and over in rapid succession. It is also desirable to have the entire circulating system as 15 nearly closed to the outside atmosphere as possible to prevent loss of the volatile detergent into the atmosphere. However, means are preferably provided for giving sufficient access to the atmosphere to prevent the formation of excess 20 vacuum or pressure conditions within the apparatus. Further, it is highly desirable to have all of the necessary apparatus and pipe connections arranged in as compact form as possible.

In accordance with my invention, the method 25 of treating fabric consists in employing a solvent having a low boiling point, for instance, carbon tetrachloride, and agitating the fabric within a pool of such solvent to remove the dirt and foreign matter from the fabric and cause its transfer to 30 the solvent. The method of recovering the solvent after a treating operation consists in evaporating it at a temperature insufficient to evaporate animal and vegetable oils and removing all 35 of the moisture therefrom which may have been extracted from the fabric being treated and then condensing the evaporated solvent only and collecting it in a storage tank from which it may be transferred to the treating point as desired, all 40 of these operations taking place in apparatus 45 partially if not wholly closed to the outside atmosphere.

The apparatus designed to carry out my method 45 comprises a storage tank for holding a supply of the treating solvent, a fabric treating compartment 50 wherein the treating operation takes place, a sump tank in which the solvent is collected after the fabric treating operation, a fan for circulating air through the treating compartment and thence through a condenser, an evaporator and then another condenser, an air heater and means for 55 selectively employing such air heater or passing relatively cold atmospheric air through the apparatus, and means for extracting all foreign matter, including moisture and oils, from the solvent after each treating operation.

Various objects and advantageous features of my invention may be seen in the following description and one embodiment thereof may be seen in the accompanying drawings wherein similar characters of reference designate corresponding parts, and wherein:

Fig. 1 is a front elevation of an apparatus embodying my invention; Fig. 2 is a plan view of the apparatus shown in Fig. 1; Fig. 3 is a rear elevation of the apparatus shown in Figs. 1 and 10 2; Fig. 4 is a sectional view taken on the line 4—4 of Fig. 2; Fig. 5 is a fragmentary detail sectional view of the sump tank constructed in accordance with my invention and shown in Figs. 1, 2, 3 and 4; Fig. 6 is a sectional view of a filter 15 constructed in accordance with my invention; Fig. 7 is a sectional view of another form of filter employed in my apparatus; Fig. 8 is a sectional view of one of the condensers; Fig. 9 is a sectional view of an air heater; Fig. 10 is a sectional plan 20 view of an evaporator having a removable steam coil; Fig. 11 is a sectional view of the same evaporator shown in Fig. 10 but showing the baffle plates; Fig. 12 is a side elevation showing the interlocking valve operating mechanism which I 25 employ; Fig. 13 is a plan view of the mechanism shown in Fig. 12; Fig. 14 is an elevation of a tub door constructed in accordance with my invention; and Fig. 15 is a diagrammatic view of the apparatus which I employ in conjunction with my 30 method for treating fabric.

Referring to the drawings, I have shown an apparatus for treating fabrics together with a means for supplying a volatile detergent to a treating compartment, removing the detergent 35 from the washer after the treating operation, and then removing the foreign matter from the detergent and transferring it to a supply tank ready for use in a subsequent operation comprising a fabric treating compartment 1 that is provided 40 on its interior with the usual rotatable goods container and is secured on one corner of a base frame 2. The rotatable goods container is driven in alternately reverse directions by a motor or power unit 3 (see Fig. 2) which is operatively 45 connected to the goods container by the usual speed reduction mechanism. Also mounted on the base frame 2, at a higher level than the treating compartment 1, is a storage tank 4 for containing a supply of the volatile liquid used in 50 the treating operation, this liquid being preferably although not necessarily carbon tetrachloride. As shown in Figs. 1, 2 and 3, a conduit or pipe 5 connects the bottom of the storage tank 4 with the treating compartment 1 and is pro- 55

vided with a valve 6 for regulating the quantity of treating medium which passes from the storage tank 4 to the treating compartment.

In order to prevent any water or moisture which 5 may collect and float on the surface of the treating medium within the storage tank 4 from gravitating into the treating compartment 1 through the conduit 5, the portion of the conduit 5 extending within the tank 4 is provided with two 10 branches. One of these branches, the branch 7, extends upwardly to a point adjacent the top of the tank 4 that is always above the level of the top surface of the treating medium within the storage tank. The other branch 8 prefer- 15 ably takes the form of a 90° elbow having its lower open end but slightly above the bottom of the tank 4 whereby the medium flowing out of the storage tank through the conduit 5 always flows from the lowermost part of the tank. A 20 small vent pipe 9 is connected to the top of the storage tank 4 and preferably extends to the exterior of the building, the pipe being open to permit air to enter the tank 4 when the medium is withdrawn therefrom and to permit the es- 25 cape of air from the tank when treating me- dium is supplied thereto.

To provide an air tight treating compartment and, at the same time, permit articles to be treated to be inserted into and removed there- 30 from, the compartment 1 has a hinged door 10 through which the goods to be treated are introduced and removed. The door 10 is equipped with suitable packing gaskets for an air tight fit and, as shown in Fig. 14, the upper edge of the 35 door has hinge pins 11 that extend into angularly extending slots 12 in brackets 13 suitably secured on the compartment 1.

At the lower edge of the door 10, two or more eccentric cams 14 mounted on pivots 15 having 40 handles 16 thereon are provided and the lower edge of the door 10 is equipped with replaceable striker plates 17 against which the cams bear in moving the door to locked position. Thus, as will be seen in Fig. 14, when handles 16 of the 45 eccentric cams are moved upwardly as shown in Fig. 14, the lower edge of the door 10 is pressed inwardly and upwardly against its seat on the treating compartment by the action of the cams and, since the slots 12 in the brackets 13 ex- 50 tend upwardly at an angle towards the compartment, the upper part of the door like the lower part thereof is forced tightly against the seat.

A conduit 18 leads from the bottom of the 55 compartment 1 to a sump tank 19 located below the compartment and is provided with a valve 20 for controlling the flow of treating medium from the compartment to the sump tank and a sight glass 21 for determining when all of the 60 medium has been drained from the compartment and has passed into the sump tank.

As shown best in Fig. 5, the outlet end of the 65 conduit 18 discharges into a strainer basket 22 that is conveniently located within the confines of the sump tank 19 and is made removable therefrom through a top opening normally closed by an air tight cover 23 (see Fig. 1). Such basket 22 is made of suitable wire mesh material and has a bail 24 by means of which it may be easily removed and replaced within the sump tank. 70 Thus, means is provided for catching and retaining any small particles of foreign matter above a given size that may have become separated from the goods in the treating compartment and 75 for preventing such foreign matter from lodg-

ing in the sump tank 19 or other parts of the apparatus and possibly interfering with the proper operation thereof.

In order to recirculate the treating medium and renovate the used medium prior to its return to the elevated storage tank 4 from which it is supplied to the treating compartment 1 for subsequent treating operations, a pump 25 is provided as well as a motor or power unit 26 and suitable connections for operating the pump. 10 As shown in Fig. 15, the intake side of the pump 25 is connected to the sump tank 19 by a conduit 27 which is provided with a branch conduit 28 under the control of a valve 29 and terminating in a free end to provide a pipe or 15 hose connection. The conduit 27 is also provided with a control valve 30 for regulating the flow of medium from the sump tank 19 to and through the pump 25. Such valve 30 is normally open while the valve 29 is normally closed. 20 However, when a fresh supply of treating medium from some outside source is to be supplied to the apparatus, the valve 30 is closed and the valve 29 is open, at which time a pipe or hose may be attached to the pipe connection 28 and 25 the fresh supply of medium drawn into the apparatus by operation of the pump 25.

As shown in Figs. 1, 5 and 15, the portion of the pipe 27 extending within the sump tank 19 terminates in a vertically extending T connection 30 whose upper end 31 is adjacent the top of the sump tank and whose lower end 32 is adjacent the bottom thereof. The purpose of a T connection of this type is to always have the intake of medium from the sump tank adjacent the 35 bottom thereof and to provide a means for regulating the lowest level of the medium in the sump tank which will be at the point where the conduit 27 joins the T connection. This is highly im- 40 portant in that it will maintain a seal for the lower end of pipe 32. A vent pipe 33 extends upwardly and outwardly from the top of the sump tank to the outside atmosphere. As shown, this vent pipe may join the vent pipe 9 leading from the storage tank 4 and extend to the at- 45 mosphere in a common vent pipe 34.

As a first step in the recirculation of the treating medium from the sump tank 19 to the storage tank 4, the medium is passed into a filter 35 by way of a conduit 36 leading from the discharge 50 side of the pump 25 and under control of a valve 37. A pipe or conduit 38 under control of a valve 39 leads from the pump discharge side or conduit 36 and terminates in a common pipe or hose connection. Normally when the apparatus is op- 55 erating, the valve 39 is closed and the valve 37 is open. However, if for any reason it is necessary to empty the system of treating medium, the valve 37 is closed and the valve 39 opened and a suitable hose or pipe attached to the connection 60 38 whereby the medium may be discharged from the system.

As shown in Fig. 6, the filter 35 comprises a cylindrical outer shell having one open end which is normally closed by an air tight removable cap 65 40 and a filtering bag 41 inside of the shell em- 70 bodying a metal ring 42 adapted to be tightly clamped between the cap 40 and the shell to form an air tight joint. The end of the shell ad- jacent the inner side of the cap 40 and the ad- jacent side of the cap are cored out to provide 75 passageways connecting the interior of the filter bag 41 with the conduit 36 and a pipe connection or conduit 43 under the control of a valve 44. Such pipe 43 connects the interior of the filter bag 75

41 with a pipe 45 which, in turn, as shown in Figs. 3 and 15, connects the filter 35 with the sump tank 19 through the conduit 27. The pipe 45 is under control of a valve 46. A pipe or conduit 5 47 connects the filter 35 with an evaporator mechanism 48 hereinafter described see Figs. 3 and 15. It will be noted that the pipe 43 is adapted to drain the liquid from the interior of the filter bag 41 while the pipe 45 is adapted to 10 drain the medium from the outside of the filter bag. Therefore, both of these pipes are disposed at and are connected to the bottom side of the filter shell. A branch pipe 49 under control of valve 50 connects the filter shell of the filter 15 35 outside of the filter bag 41 with the storage tank 4 through a portion of pipe 47.

In the operation of this part of the apparatus, when the system is in operation, the valve 31 is open and the valves 44, 46 and 50 are closed, 20 whereby the treating medium is pumped from the sump tank 19 by the pump 25 and through the pipe 36 into the interior of the filter bag 41, through the bag and into the outer shell of the filter 35, and thence through the pipe 47 into the main evaporator 48 where the filtered medium is converted into the vapor and thereafter rises 25 and passes through the pipe 51 into a condenser 52, also hereinafter described. Within this condenser, the vapor is converted into liquid which 30 gravitates through the pipe 53 provided with a sight glass 53' and into the storage tank 4. The pipe 47 is provided with a check valve 54 to prevent liquid from flowing backwardly from the evaporator 48 and into the filter 35. Also, to 35 permit air to enter the filter 35 to compensate for the liquid flowing out of the filter shell or cylinder during the draining operation, a petcock 55 as shown in Figs. 3 and 6 is attached to the upper part of the filter 35 and may be conveniently 40 placed in the pipe 47 as shown.

At times it becomes necessary to clean out the filter 35 and at such time the valve 31 in the pipe 36 is closed and the valves 44 and 46 are open which will permit the treating medium from 45 in the filter bag 41 and from within the outside shell of the filter to gravitate through the pipes 43 and 45 and a part of pipe 27 into the sump tank 19. After the medium has all drained from the filter 35, the cap 40 may be removed and the 50 filter bag 41 drawn out of the shell and cleaned whereupon it may be replaced in the shell and the cap 40 secured in place whereupon the filter is again in condition to properly function.

To further remove any water or moisture from 55 the medium that has passed through the filter, evaporator, and condenser, and is passing into the storage tank, from entering the storage tank, a waste trap 56 as shown in Figs. 1, 2, 3, 7 and 15, is provided in the conduit leading from the 60 condenser 52 into the storage tank, the trap being provided with a removable cap 57 and being adapted to receive a quantity of cotton waste 58 through which the medium entering the storage tank must pass. A pipe 59 extends downwardly 65 from the waste trap to a point a short distance above the bottom of the storage tank 4 which provides a liquid seal for the pipe 59 at all times and prevents any agitation of the contents when it is being filled by liquid entering 70 through the pipe. Skimming valves may be provided in the storage tank if desired.

While the capacity of the evaporator 48 is 75 preferably sufficient to supply enough treating medium to the storage tank 4 to permit continuous operation of the apparatus and, at the

same time, complete a generous supply of medium in the storage tank 4, an auxiliary evaporator 60 is provided to remove the remaining medium in the sludge removed from the main evaporator. This auxiliary evaporator is positioned at a lower 5 level than the main evaporator 48 so that it is only necessary to open the valve 61 provided in a conduit 62 that leads from the bottom of the evaporator 48 and into the evaporator 60 to supply sludge medium to the auxiliary evaporator. 10 As shown, particularly in Figs. 2 and 15, a discharge vapor pipe 63 leads from the top of the auxiliary evaporator 60 and into the discharge pipe 51 leading from the top of the main evaporator to the condenser 52. A drain pipe 64 under 15 control of a valve 65 is provided on the bottom of auxiliary evaporator 60 for cleaning out purposes. Both evaporators 48 and 60 have steam supply pipes 66 connected thereto for providing the necessary heat and the condenser 52 has cold water 20 supply pipes 66' connected thereto for reducing the temperature in such condenser.

The construction of the main evaporator 48 previously referred to is shown in Figs. 10 and 11 wherein the main body portion 48 is shown as 25 being closed at the top and bottom and as being provided with a vapor discharge pipe 51 at the top and a sludge discharge pipe 62 at the bottom thereof. At a point intermediate the ends of the body portion and preferably above the center 30 thereof is a horizontal partition 67 having its central portion in the form of a cone with its apex cut away to provide an opening 68. A screen 69 is secured across the base of the cone to intercept the foam arising from the heated cleaning 35 liquid.

A plurality of brackets 70 are positioned just above the partition 67 and support a cone 71 whose largest diameter is somewhat smaller than the inside diameter of the evaporator shell so as 40 to form an opening between the base of the cone and the evaporator shell through which the vapor must pass on its course to the outlet pipe 51. These partitions or baffles provide a means for preventing foaming or priming and forcing of 45 dirty medium through the lines into the storage tank. In operation, the vapor rises from the surface of the heated medium, passes through the screen 69, thence upwardly through the opening 68, thence outwardly and upwardly through the 50 opening between the cone 71 and the shell of the evaporator and finally through the outlet pipe 51, the liquid of condensation above and below the partitions or baffles draining back to the bottom of the evaporator through a pipe 73. 55

The evaporator 48 is also provided with readily removable steam coils 74 as shown in Fig. 10 wherein the evaporator body is shown as being provided with an opening 75 having a border flange 76 to which is removably secured a plate 60 77 and cap 78. The open ends of the steam coil 74 are rigidly secured in the plate 77 and a steam inlet 79 is provided in the cap 78. In operation steam is forced into the inlet 79 and thence passes into and through the coil 74, all water of condensation passing out through a drain opening or pipe 80. It will be noted that the opening 75 is sufficiently large to permit passage of the coil 74 therethrough when the cap 78 and plate 77 are removed. 70

The steam supply pipe 66 leading to the main evaporator 48 as well as to the auxiliary evaporator 60 receives its supply from a main supply pipe 89 and is provided with a valve 90 operable by a rod 91 that slides freely through the perfo- 75

- 5 rated end of the valve lever 92. Adjustable stops 93 and 94 are fixed on the rod 91 above and below the lever 92 to contact with opposite sides of the lever and move the same to open or close the valve as the rod is raised or lowered. The lowermost end of the rod 91 is fixed to a float 95 that rides on the surface of the medium in the sump tank 19 and the parts are so arranged and connected that the valve will be automatically 10 operated by raising or lowering of the float as the level of the medium in the sump tank rises or falls above or below the predetermined level. Thus, means is provided for automatically controlling the supply of steam to the evaporators. 15 The switch controlling the operation of the motor 26 which drives the pump 25 may be connected to and operable by the rod 91 whereby the flow or movement of the treating medium from the sump tank to the evaporator is automatically 20 regulated by the amount of medium in the sump tank.

A single operating handle or lever 96 is provided at the front of the device for selectively operating either the supply valve 6 which controls 25 the flow of medium from the storage tank 4 to the treating compartment 1 or the drain valve 20 which controls the flow of fluid from the washer compartment 1 to the sump tank 19, but only one thereof at any time. The construction 30 of the hand lever 96 to effect such operation of the two valves is best illustrated in Figs. 12 and 13 wherein the lever is shown as being mounted between the crank arm 97 which is connected to the supply valve 6 by a rod 98 and a crank 35 arm 99 which is connected to the drain valve 20 by means of a rod 100. Both of the arms 97 and 99 and the lever 96 are loosely pivoted on a short supporting shaft 101 that is secured in the frame of the machine. As seen in Fig. 13, the hub of 40 the lever 96 is arranged to operate each of the valves through a lost motion connection including integral lever lugs 102 and 103 extending oppositely and in the path of cooperating lugs 104 and 105 on the crank arms 97 and 99 respectively, these cooperating lugs being so arranged that swinging of the lever 96 on its pivot in one direction will cause the rotation of the crank arm 97 about its pivot, but without effect upon the other valve, and swinging of the lever 45 96 in the opposite direction will move the crank arm 99 about its pivot, again without effect upon the other valve. Suitable springs 106 as shown in Fig. 4 may be provided for returning the valves to their normal position after operation by movement 50 of the respective crank arms connected thereto. This operating mechanism is so constructed that when the lever 96 is in neutral position both valves 6 and 20 are held in closed position by the springs 106.

55 In addition to the hereinbefore described apparatus for recirculating and renovating the treating medium, suitable apparatus has been provided for deodorizing and drying the goods as a part of the treating operation and before removal of the goods from the washing compartment. As shown in the drawings, a fan 107 is located near the treating compartment 1, the fan being driven by a motor 108. One discharge of the fan is connected by means of a duct 109 60 to an air heater 110 which is, in turn, connected to the treating compartment 1 by a duct 111. An air duct 112 connects the compartment 1 with a condenser 113 and the air discharge of this condenser is connected by duct 114 to the intake side 65 of the fan 107. The liquid discharge from the 70

condenser 113 passes through a pipe 115 to a point within and close to the bottom of the sump tank 19. Such pipe has a sight glass 116 therein for determining when liquid is flowing from the condenser 113 to the sump tank.

The condenser 113 has one end closed by a perforated plate 81, the plate providing a supporting means for a plurality of tubes 82 which are open at one of their ends. Such tubes 82 extend inside the condenser to practically the opposite wall where they are closed by suitable plugs 83. A second plate 84 is spaced a short distance from the plate 81 and provides a supporting means for a plurality of open ended tubes 85 that are smaller than tubes 82 and register with the tubes 82 in a manner as to be disposed within such tubes when the apparatus is in assembled relation, the tubes 85 terminating a short distance from the plugs 83 in the tubes 82. A third plate 86 is spaced a short distance from the plate 84 and is provided with a water inlet 87. In the operation of this part of the apparatus, cold water from pipe 66' flows into the inlet 87, thence through the small tubes 85, thence back through the large tubes 82 and into the space between the plates 81 and 84 and thence out through the outlet pipe 66'. Therefore, hot vapor forced through the main container around the pipes 82 becomes cool and is converted into liquid, finally passing through the pipe 115 and into the sump tank.

In the drying operation, the fan 107 is placed in operation whereby air from the heater 110 will be forced through the compartment 1 and will gather vapor from the goods therein and carry such vapor through duct 112 to the condenser 113, wherein the treating medium is condensed, the air passing onwardly through duct 114, fan 107, duct 109, and heater 110 back through the compartment 1 while the condensed vapor removed therefrom passes through the pipe 115 to the sump tank 19. It will be understood that the air is reheated at each passage through the heater 110 and that the air is continuously circulated through the compartment until the condensed liquid ceases to pass through the pipe 115, that is, until there is no more treating medium in the goods to be picked up by the moving air, and visible through sight glass 116. 35 40 45

Means are also provided for deodorizing the goods in the treating compartment. This deodorizing operation takes place after the drying operation just described. Suitable air valves 117, 118 and 119 are provided at convenient places in the various parts of the air circulating system and are operable simultaneously and by a single means and held in normal closed position by a single spring 120. After the drying operation, the air valves 117 and 119 are opened, and valve 118 is closed by moving a suitable lever 117 which will permit atmospheric air to be drawn into the system through the valve 119, passed through the dried goods in the compartment 1 and thence be discharged through duct 112, condenser 113, duct 114, fan 107, valve 117 and duct 121 to the atmosphere. Such forced circulation of atmospheric air through the treated goods is continued until the goods are thoroughly deodorized after which they are removed from the compartment 1 and a fresh batch to be cleaned is introduced. As shown in Figs. 1, 2 and 4, one or more fine wire screens 122 are removably placed in the duct 112 to intercept or collect any fine dust or lint passing with the air to the condenser 113. 50 55 60 65 70 75 80

The construction of the air heater 110 is shown in Fig. 9 wherein the open end of the shell or condenser is closed by a plate 123 which supports the open ends of a plurality of bent tubes 124. A second plate 125 is spaced a short distance from the plate 123 and both plates are rigidly secured to the main body portion or shell or container by suitable means. The plate 125 is provided with a steam inlet pipe 126 through which steam is supplied that passes to and through the pipes 124 over which the air passes in its circulation. An opening 127 is provided to relieve the space between the plates 123 and 125 of any water of condensation.

10 Suitable push button mechanism 128 on a panel board 129 controls the operations of the pump motor 26 and the fan motor 108. The treating compartment motor 3 is controlled by a hand lever 130 provided adjacent the hand lever 96 15 and the supply of steam coming from the main supply pipe 89 to the air heater 110 is controlled by a valve 131' under control of an operating means 131 on the panel board. Another valve 132' under control of an operating means 132 on 20 the panel board is provided for controlling the flow of water through the pipe 66' to the condenser 113 and thence through another pipe 66' to condenser 52.

A part of my improved apparatus for treating 30 fabrics consists in the provision of an apparatus of such construction that the treating medium during the treating operation, does not have free communication with the atmosphere as does the medium in the storage tank which has free communication with the atmosphere at all times 35 through the vent pipe 9. As hereinbefore described, the vent pipe 33 for the sump tank 19 has its open end above the surface of the medium in the sump tank (see Fig. 5) whereby no 40 seal is maintained against free communication between the gas space in the sump tank and the atmosphere. However, the compartment 1 does not have free communication with the gas space of the sump tank, due to the normally closed valve 20.

It is also desirable to prevent free communication from the treating compartment to atmosphere at any time when the treating compartment contains an appreciable quantity of volatile solvent or is in open communication with any container which contains such solvent. Free communication of the treating compartment to atmosphere occurs only when the air valves 117, 118 and 119 are in the one pass position with atmospheric air openly admitted at 119 to flow through the treating compartment and condenser to atmosphere at 121. I therefore provide an interlocking connection between the air valves or their operating means, on the one hand, and 50 the valves 6, 20, or their operating means, on the other hand, which control communication to the treating compartment of the storage reservoir and sump tank respectively, such interlocking connections preventing movement of the air 55 valves to the one pass position when either of the valves 6, 20 is open, and also preventing opening of either of the valves 6, 20 when the air valves are in the one pass position.

This mechanism comprises a bell crank lever 70 133, best shown in Figs. 1, 2 and 4, and having two arms, one hooked or bent and the other straight, which respectively cooperate with the lever 96 which controls valves 6 and 20 and with the lever 117' which controls the air valves. 75 The bell crank lever is pivoted at 134 to a por-

tion of the machine frame and its normal position is shown in Fig. 2, where both of the levers 96 and 117' are also shown in normal position, that is, with the valves 6, 20 both closed and the air valves in the repeated circulation position illustrated in Fig. 15.

Assuming the parts, then, in the position of Fig. 2, if the lever 117' is moved down (in Fig. 2) to shift the air valves to the one pass position, said lever engages and operates the straight arm 10 of lever 133, turning it clockwise in Fig. 2 and hooking its bent arm around the lever 96, so as to lock the same in its intermediate or neutral position, and preventing it from being moved to open either valve 6 or valve 20.

Again assuming the parts in the position shown in Fig. 2, if the lever 96 is moved either up or down to operate one or the other of the valves 6, 20, as the case may be, the lever 96 comes to a position opposite the end of the bent arm of 20 lever 133 or to a position adjacent the shank of said bent arm, and in either case, the lever 96 in its new position now serves as an abutment which locks and prevents movement of the bell crank lever 133 and therefore holds said lever in 25 effect stationary, so that it obstructs and prevents any movement of the lever 117' to actuate the air valves and, perforce, compels said air valves to remain in the repeated circulation position of Fig. 15, so long as either valve 6 or valve 30 20 is open.

The sump tank 19 is provided with an overflow pipe 135 which enters the top of the sump tank and extends downwardly inside the tank to a short distance of the bottom thereof to always 35 form a liquid seal between the outside atmosphere and treating medium within the tank. As shown, the upper end of the overflow pipe above the top of the tank is provided with an inverted U bend 136 to prevent any foreign matter 40 entering the sump tank through the overflow pipe. One end of the sump tank is provided with a sight glass 137 whereby the level of the medium in the sump tank may be observed.

A quantity of moisture will be extracted from 45 the goods in the treating compartment during each treating operation, a part of this moisture being taken up with the hot air during the drying step previously described and passing into the condenser and then finally draining back 50 into the sump tank. The remaining part of such moisture passes with the treating medium through the conduit 18 directly into the sump tank where- 55 in all moisture floats on the surface of the medium so that none of it is drawn from the sump tank by the pump 25 hereinbefore described. Long continuous use will cause a considerable quantity of moisture or water to gather super- 60 posed upon the surface of the medium in the sump tank and this water may be drawn off, 65 whenever necessary, through a water drain valve 138 provided at one end of the sump for that purpose.

In some plants it may be preferable to connect 65 the top of the treating compartment 1, the storage tank 4, and the sump tank 19 by suitable piping 139 shown by the dotted lines in Fig. 15. In this event, the vent pipe 34 could either remain open so that the entire system is open to the atmosphere or the vent pipe 34 could be closed 70 after the apparatus is once filled with liquid whereby the entire system would be closed to the atmosphere during the treating operation.

Referring to the drawings and the preceding description, it will be seen that I have provided

an apparatus for treating fabrics embodying numerous novel and advantageous features. For instance, I have provided a fabric cleaning apparatus of such nature that, while the fabric treating compartment is sealed against free communication with the atmosphere and the storage tank from which a supply of treating medium is taken may or may not have free communication with the atmosphere. Another advantageous feature resides in the fact that means is provided for admitting atmospheric air to the fabric treating compartment for deodorizing the fabric after a treating operation together with control mechanism which will prevent treating medium from the storage tank from entering the fabric cleaning compartment during the time such atmospheric air is being admitted thereto.

Still another advantageous feature resides in the fact that I have provided an apparatus embodying means for collecting and removing any water which may collect in and become mixed with the treating medium. It is well known that water and some treating mediums, particularly, carbon tetrachloride, form destructive acids which, when allowed to remain in the apparatus, will in time destroy the apparatus. This destructive feature is eliminated primarily by the provision of means for collecting the water in the sump tank, preventing it from being drawn into the other parts of the apparatus, together with means for removing such water at various times. Various other novel and advantageous features will be readily apparent.

What I claim is:

35 1. Dry cleaning apparatus wherein fabric is subjected to treatment with a volatile solvent, comprising a treating vessel, a condenser, means for circulating air in a closed path between the condenser and treating vessel, a collecting vessel 40 for said solvent, means for maintaining a minimum level of solvent liquid therein, said collecting vessel being vented to atmosphere, and a drain connection from said condenser communicating with said collecting vessel below said minimum level of liquid.

45 2. Apparatus of the character described in claim 1, including a drain pipe from the treating vessel to said collecting vessel.

3. Dry cleaning apparatus wherein fabric is 50 subjected to treatment with a volatile solvent which is heavier than water, comprising a treating vessel, a condenser, means for circulating air in a closed path between the condenser and treating vessel, a collecting vessel for said solvent, means for maintaining a minimum level of liquid therein, said collecting vessel being vented to atmosphere, a drain connection from said condenser communicating with said collecting vessel below said minimum level of liquid, and a drain 55 connection from said collecting vessel at a level above said minimum liquid level therein, for skimming therefrom any water layer superposed upon the solvent liquid.

60 4. Apparatus of the character described in claim 3, including a drain pipe from the treating vessel to the collecting vessel.

65 5. Dry cleaning apparatus wherein fabric is subjected to treatment with a solvent which is heavier than water, comprising a treating vessel, a condenser, means for circulating air in a closed path between the condenser and treating vessel, a sump tank vented to atmosphere, apparatus for reclaiming used solvent, means for conducting 70 the solvent from the sump tank to said appa-

ratus and arranged to maintain a minimum level of liquid in the sump tank, a drain connection from said condenser communicating with the sump tank below the minimum level of liquid therein, and a drain connection from said sump tank at a level above the minimum level of liquid therein for skimming therefrom any water layer superposed upon the solvent liquid.

7. Dry cleaning apparatus wherein fabric is subjected to treatment with a volatile solvent, comprising a treating vessel, a condenser, means for circulating air in a closed path between the condenser and treating vessel, a vessel containing liquid solvent and vented to the atmosphere, and a drain connection from said condenser communicating with said vessel containing liquid solvent below the level of liquid therein.

8. Dry cleaning apparatus wherein fabric is subjected to treatment with a volatile solvent comprising conduit connections extending from said apparatus to atmosphere, said conduit connections including a liquid seal and a liquid drain 25 from said apparatus to said liquid seal.

9. Dry cleaning apparatus wherein fabric is subjected to treatment with a volatile solvent comprising a treating circuit and a reclaiming circuit, and conduit connections extending from at least one of said circuits to atmosphere, said conduit connections including a liquid seal and a liquid drain 30 from at least one of said circuits to said liquid seal.

10. Dry cleaning apparatus wherein fabric is 35 subjected to treatment with a volatile solvent comprising a reclaiming circuit and conduit connections extending from said reclaiming circuit to atmosphere, said conduit connections including a liquid seal and a liquid drain 40 from said reclaiming circuit to said liquid seal.

11. Dry cleaning apparatus wherein fabric is subjected to treatment with a volatile solvent comprising a treating circuit and conduit connections extending from said treating circuit to atmosphere, said conduit connections including a liquid seal and a liquid drain 45 from said treating circuit to said liquid seal.

12. Dry cleaning apparatus wherein fabric is 50 subjected to treatment with a volatile solvent, comprising a treating circuit including a washer and a condenser, a sump tank, conduit connections extending from at least one of the vessels in the group consisting of said washer and said condenser, to atmosphere by way of said sump tank and including the liquid in said sump tank as a seal.

13. Dry cleaning apparatus wherein fabric is 55 subjected to treatment with a volatile solvent, comprising a treating circuit, a sump tank, and conduit connections extending from said treating circuit to atmosphere by way of said sump tank and including the liquid in said sump tank as a seal.

14. Dry cleaning apparatus wherein fabric is 60 subjected to treatment with a volatile solvent, comprising a sump tank having a vent to the atmosphere, a drain connection from the portion of said apparatus above the sump tank to said sump tank, the liquid in said sump tank constituting a seal between said vent and said drain, and means for maintaining a minimum level of liquid in said sump tank.

15. Dry cleaning apparatus wherein fabric is

subjected to treatment with a volatile solvent, comprising a sump tank vented to the atmosphere, a drain extending to the bottom of the sump tank from another part of the apparatus, and means for maintaining a minimum level of liquid in said sump tank.

16. Dry cleaning apparatus wherein fabric is subjected to treatment with a volatile solvent comprising a treating circuit, a sump tank for containing solvent, a vent pipe extending from the treating circuit to the lower portion of said sump tank, means for transferring liquid from the bottom portion of said sump tank to another part of the apparatus, and means for rendering 10
15 said transferring means inoperative before the

level of liquid in said sump tank falls below the lower end of said vent pipe.

17. Dry cleaning apparatus wherein fabric is subjected to treatment with a volatile solvent, comprising a treating circuit, a sump tank for containing a solvent, an evaporator, a vent pipe extending from the treating circuit to the lower portion of said sump tank, means for transferring liquid from the bottom portion of said sump tank to the evaporator, and means for rendering 10
15 said transferring means inoperative before the level of liquid in said sump tank falls below the lower end of said vent pipe.

RUSSELL A. HETZER. 15
